ALPHONSE DUTHIL, OF MÉZIÈRES, FRANCE.

FILE FOR LETTERS OR THE LIKE.

1,117,648.

Specification of Letters Patent. Patented Nov. 17, 1914.

Application filed October 20, 1913. Serial No. 796,260.

To all whom it may concern:

Be it known that I, ALPHONSE DUTHIL, a citizen of the Republic of France, and resident of Mézières, Ardennes, France, have 5 invented new and useful Improvements in or Relating to Files for Letters or the like, which are fully set forth in the following specification.

This invention proposes an improved 10 clamp, chiefly applicable to files, records, loose-leaf pocket books, cases etc., to enable documents such as business papers, invoices, letters etc. to be quickly filed and bound without requiring the formation of perforations therein.

The accompanying drawings show by way of example several constructions according to this invention.

Figure 1 is a side elevation of the clamp 20 applied to a file; Fig. 2 is a horizontal section on line A—A, Fig. 1; and Figs. 3 and 4 are diagrammatic side views of a construction applicable to loose-leaf pocket books.

25 Against the back 1 of the file (Figs. 1 and 2) is securely fitted a member 2, which has its ends bent inwardly so as to form grooves 3. These grooves afford guidance to a metal bar 4 extending entirely across 30 the file and having projections at its ends, to engage the said grooves 3, the projections being here shown as produced by recessing the bar ends. The bar 4 thus engaged in the guide grooves is enabled to move bodily 35 therein toward and from a similar bar 5 secured to the member 2, the two bars forming a pair of jaws between which may be arranged the sheets 11 for separating the documents subsequently filed.

40 A chain 7 or other suitable flexible element connected to one or more helical springs 10, is arranged in the opposed grooves 6 provided in the bars 4 and 5 adjacent the front, longitudinal edges thereof, 45 said chain passing through the openings 8 in the ends of the said bars. The chain and the helical springs constitute an expandible device which, passing around the two bars, serves to tightly clamp the contained documents. In passing through the openings 8, 50 the chain can be guided either by rollers 9 or by giving a suitable curvature to the grooves 6 at such points, or by other suitable means. Moreover one or more of these

devices may be arranged around the two 55 bars.

The same tightening action is obtained if the expandible device or devices, instead of surrounding the two bars, pass along the groove of the movable bar alone, and their 60 ends are secured at suitably selected points on one of the flat covers or boards of the file.

Figs. 3 and 4 show a construction which is applicable to loose leaf pocket books. 65 The two mounts *a* and *b* replace the bars previously described. They are connected by one or more hinges *c* and are designed to receive in the grooves *d* the expandible tightening device previously described. 70

This invention thus brings about automatic tightening of documents, and when a sheet is introduced it is automatically gripped and held in place without requiring to be perforated. 75

Claims:

1. A clamp for loose-leaf files and the like, comprising a pair of superposed bars adapted to receive between them the documents to be bound and formed with inwardly-projecting, longitudinal channels coincident in length therewith and having openings adjacent the ends of the channels; and an endless tightening device for drawing said bars together passing along said 85 channels and through said openings.

2. A clamp for loose-leaf files and the like, comprising a pair of superposed bars adapted to receive between them the documents to be bound, said bars being formed 90 with inwardly-projecting, longitudinal channels coincident in length therewith and having openings adjacent the ends of the channels; and an endless tightening device for drawing said bars together embodying 95 a spring disposed in the channel of one bar and a chain disposed in the channel of the other bar and having its ends passed vertically through the openings in both bars and connected to the ends of said spring. 100

In testimony whereof I have signed this specification in the presence of two subscribing witnesses.

ALPHONSE DUTHIL.

Witnesses:

EMILE LEIDRET,
HANSON C. COXE.
